HOOD ORNAMENT

Claude Genest, Oak Park, Mich., assignor to
General Motors Corporation, Detroit, Mich., a
corporation of Delaware

Application December 23, 1953, Serial No. 28,182

Term of patent 7 years

(Cl. D14—18)

To all whom it may concern:

Be it known that I, Claude Genest, a citizen of the Republic of France, a resident of Oak Park, Michigan, have invented a new, original, and ornamental Design for a Hood Ornament, of which the following is a specification, reference being made to the accompanying drawing, forming a part thereof.

In the drawing:

Fig. 1 is a top plan view of a hood ornament showing my new design;

Fig. 2 is a side elevational view thereof;

Fig. 3 is a front elevational view thereof; and

Fig. 4 is a sectional view taken along the line 4—4 of Fig. 3.

I claim:

The ornamental design for a hood ornament, substantially as shown.
